UNITED STATES PATENT OFFICE

2,145,768

AGITATOR

William C. Knapp, Columbia, Pa.

Application February 7, 1938, Serial No. 189,249

1 Claim. (Cl. 259—50)

This invention appertains to new and useful improvements in agitators in the form of a drum for use in washing, cleaning or drying material.

The principal object of the present invention is to provide an agitating drum wherein material is treated by a lifting and dropping action.

Another important object of the invention is to provide a material treating drum which will in operation reduce the time interval required in 10 treating material over the use of machines now generally in use.

Other important objects and advantages of the invention will become apparent to the reader of the following specification.

15 In the drawings:—

Figure 1 represents a fragmentary vertical sectional view through a tub showing the improved drum mounted therein.

Figure 2 is a cross sectional view on the line 20 2—2 of Figure 1.

Figure 3 is a fragmentary top plan view of the drum.

Figure 4 is a fragmentary perspective view of one of the ribs.

25 Figure 5 is a side elevational view of the drum constructed of sheet metal.

Figure 6 is a cross section on the line 6—6 of Figure 5.

Referring to the drawings wherein like numerals designate like parts, it can be seen in Figure 1 that numeral 5 represents the tub with the top 6, while numeral 7 generally refers to the drum mounted on pintles 8—8 in the tub 5.

As shown in Figures 2 and 3, this drum 7 includes the end walls 9, the type of drum shown in Figures 1, 2 and 3 is of wood and has the perforated side walls 10—10 each extending for approximately ninety degrees around the drum with the intervening spaces taken up by the lifts 40 11—12 and the doors 13—14.

The lifts 11—12 extend inwardly of the drum and are on spaced parallel planes with respect to each other and on opposite sides of a line drawn diametrically through the drum.

45 At one end portion of each of the walls 10 is located a rib 15 having suitable fastening means 16 thereon complementary with means on the corresponding doors 13 or 14 for securing the door in place and these doors 13—14 are hingedly secured to cleats 16 which, in turn, are suitably secured to the inner edges of the lifts 11—12 as shown in Figure 2.

Strengthening ribs 17 extend longitudinally of the drum as is clearly shown in Figure 2.

55 Obviously, the drum traveling in the direction of the arrow in Figure 2 will lift material in the drum upwardly on the corresponding lift 11 or 12 and when the material has been lifted to the

top drum it slides off and drops to the bottom of the drum, this dropping action is a substitute for the pounding and jarring action of other types of drums, the same being much more gentle to the material while being just as effective and as will be observed, this dropping action occurs twice during each revolution of the drum with the material falling through a space, the entire height of the drum.

Figures 5 and 6 represent a slight modification 10 of the invention in that the drum is constructed of the sheet metal cylinder 18 connecting the end walls 19, this cylinder 18 being perforated and having an opening permitting access to the interior which is normally closed by the slide 15 closure 19 slidable on the guide rails 20.

The cylinder 18 is preferably constructed in sections with the ends of the sections spaced as at 21 but connected together by inwardly disposed perforated channeled ribs 22 which serve 20 to strengthen the cylinder.

The perforated lifts 23—24 are also of sheet metal, being reinforced by channeled cleats 25 at their free edge portions and being secured at their attached edge portions by cleats 26 to the inside 25 of the cylinder 18.

While the foregoing specification sets forth the invention in specific terms, it is to be understood that numerous changes in the shape, size and materials may be resorted to without departing 30 from the spirit and scope of the invention as claimed hereinafter.

Having described the invention, what is claimed as new is:—

An agitator comprising a cylindrical structure 35 mounted for rotation within a solution of a container and including a cylindrical wall and end walls of solid formation, said cylindrical wall being composed of pairs of perforated arcuately curved sections and a pair of inwardly extending 40 perforated lift plates abutting said sections at the outer ends thereof, perforated doors extending angularly to said lift plates, cleats extending longitudinally of the cylindrical structure and mounted on the end walls and having notches to 45 receive the inner ends of the lift plates and having said doors hinged thereon, ribs extending longitudinally of the cylindrical structure between the end walls and abutting the perforated sections and providing stops for the doors, fasteners de- 50 tachably securing the doors on the stops, and ribs extending longitudinally of the cylindrical structure and arranged between and in abutting engagement with the sections of each pair of sections and projecting beyond the inner faces of 55 said sections.

WILLIAM C. KNAPP.
